UNITED STATES PATENT OFFICE.

GEORGE W. BLANCHARD, OF ST. LOUIS, MISSOURI.

RAIL-SPICE.

No. 897,707.

Specification of Letters Patent.

Patented Sept. 1, 1908.

Application filed March 29, 1907. Serial No. 365,371..

To all whom it may concern:

Be it known that I, GEORGE W. BLANCHARD, a citizen of the United States of America, residing at St. Louis, in the county 5 of St. Louis City and State of Missouri, have invented new and useful Improvements in Rail-Splices, of which the following is a specification.

This invention relates to rail splices, and 10 one of the principal objects of the same is to provide a rail splice in which the pounding of the rolling stock at the joint will be obviated.

Another object of the invention is to provide a joint which will not require the use of 15 fish plates and will not sink at the joint.

Still another object of the invention is to provide a rail splice which will obviate the pounding of the rolling stock against the rail joint, will always hold the rails firmly in position, will obviate spreading or sinking or 20 creeping, the ends of the rails being confined within a chair which fits over the base flanges of the rails and extends beyond the joint.

These and other objects may be attained 25 by means of the construction illustrated in the accompanying drawings, in which:

Figure 1 is a side elevation of a rail splice made in accordance with my invention. Fig. 2 is a plan view of the same. Fig. 3 is a 30 vertical section; and Fig. 4 is a perspective view of one of the meeting ends of one of the rails.

Referring to the drawing for a more particular description of my invention, the numerals 1 designate the meeting ends of a pair of railway rails in which the tread portion, the web, and the base flange are cut away on a median line vertically for a distance back of the outer end of the rail, thus providing a 35 shoulder 2 against which the terminal end 3 of the oppositely disposed rails abut. The rabbeted ends of the rail thus form a continuous tread surface for the rolling stock

only broken by a lateral joint extending across one half of the tread surface of the 45 rail and disposed upon opposite sides thereof. The web portions of the rabbeted ends 4 of the rails are provided with through slots 5 for the bolts 6, thus permitting expansion and contraction of the rails without interfering with the splice. A rail chair 7 extending beyond the ends of the rails is provided with spike apertures 8 by means of which the 50 chair is spiked to the ties. The chair 7 is provided with flanges 9, said chair being hollow and provided with a recess through 55 which the ends of the rails are inserted and brought together for the through bolts 6.

From the foregoing it will be obvious that a rail splice made in accordance with my invention is of comparatively simple construction, does not require fish plates, will obviate spreading, sinking or creeping of the rail 60 ends, and can be easily attached and connected to the ties.

Having thus described the invention, what I claim is:

The herein described rail splice comprising rails, the ends of which are provided with rabbets formed on vertical lines extending 70 through the tread portion, the web and the flange of the rails, a chair for inclosing the base flanges of the rails, said chair having inwardly extending flanges bearing at their inner edges against the sides of the webs of the 75 rails, said chair being formed in a single piece and having spike notches in the outer edges thereof, and bolts passing through slots in the web portions of the rabbeted ends of the rails, substantially as described.

In witness whereof, I affix my signature in presence of two witnesses.

GEORGE W. BLANCHARD
